UNITED STATES PATENT OFFICE.

EDWARD B. MEATYARD, OF GENEVA, WISCONSIN.

COMBINED CAR BRAKE AND COUPLER.

SPECIFICATION forming part of Letters Patent No. 293,263, dated February 12, 1884.

Application filed July 7, 1882. (No model.)

To all whom it may concern:

Be it known that I, EDWARD B. MEATYARD, a citizen of the United States, residing at Geneva, in the county of Walworth, in the State 5 of Wisconsin, have invented certain new and useful Improvements in Combined Car Brakes and Couplers, which are fully set forth in the following specification, reference being had to the accompanying drawings, in which—

10 Figure 1 is a top plan view of a car-truck provided with my improvements. Fig. 2 is a bottom plan view of the same broken away at one side. Fig. 3 is a section on the line $x-x$ in Fig. 1. Fig. 4 is a section on the 15 line $y-y$ in Fig. 1, the intersected wheels not being shown. Fig. 5 is an enlarged side elevation of the brake-shoe with part of the wheel to which it is applied. Fig. 6 is a front elevation of the coupling mechanism. Fig. 7 is 20 an enlarged side elevation of the same. Fig. 8 is a vertical longitudinal section of the same. Fig. 9 is a section on the line $z-z$ in Fig. 8.

The same letters denote the same parts in all the figures.

25 My invention relates to railway-cars in which the brakes are automatically operated by the coupling apparatus; and the objects of it are, first, to provide a link-coupling mechanism more readily attachable and detachable than 30 those now in use; and, second, to provide a braking mechanism automatically operated by the coupling mechanism, so that the brakes shall always be applied, except when motion is communicated to the train from the loco- 35 motive, and that in the latter case, whichever the direction of the motion, the brakes shall be taken off, and this by devices much simpler and less expensive than any automatic braking mechanism now in use.

40 To these ends it consists, partly, in the combination of the traction-springs with a lever having a fixed fulcrum, with a rod pivoted to one arm of the lever after the manner of a toggle-joint, and with mechanism pivotally 45 connecting the rod with the brake-bars, so that the latter shall be forced apart or drawn toward each other, according as the lever and rod are brought into or out of a continuous line by the elasticity of the springs; and it 50 consists, further, in the several devices and combinations of devices, which I will now pro-

ceed to describe, and will afterward point out definitely in the claims.

In the drawings, A denotes a pair of longitudinal beams, which aid in supporting the 55 flooring of the car.

B denotes the buffer, which is a rectangular box in general form, but enlarged at the front end, where it is open, into a flaring circular rim, B'.

60 The coupler C, which is inclosed within the buffer, is in general form an I-beam, its flanges resting, respectively, against the top and bottom of the buffer, and its web, which extends for but a comparatively short distance between 65 the middle parts of the flanges being re-entrantly curved at its forward end. This coupler is rigidly attached near its inner end to the draw-bar D by means of a pin, C', passing through holes in the flanges of the coupler 70 and through an eyed nut, D', which screws onto the forward end of the draw-bar. This pin passes through slots in the upper and lower plates of the buffer, by means of which the coupler has a limited longitudinal play 75 in the buffer. Similar slots in the flanges of the coupler toward its forward end admit the passage of another upright pin, C'', whose lower end rests on the bottom of the buffer, 80 while its upper end passes through a hole in the top of the buffer and rises a short distance above it. The hole is just large enough to allow an easy upward-and-downward movement of the pin. Through the upper end of this pin passes a horizontal pin, E, which extends beyond the buffer on each side, and is secured at each end in an upright rod, E'. The rods E' pass each through a guide-lug, B'', on its side of the buffer to a point some distance below it, where their lower ends are connected 85 by another horizontal pin, E'', the rods E' and pins E and E'' forming a clevis, which keeps the pin C'' upright and limits its upward motion. Around the middle of the pin E'' is passed the forward end of a bar-spring, F, the 90 rear end of which is rigidly attached to the lower plate of the buffer, near its rear end. This spring draws the pin C'' downward whenever the buffer is pushed in, and at the same time checks the force of its descent, so 95 that its lower end does not strike the bottom of the buffer violently. The spring is made 100

light, so that there may be no difficulty in raising the pin C² when necessary, to let the coupling-link G pass behind it.

One great difficulty in the practical working of traction-brakes heretofore has been that they have been applied to standard coupler and buffersprings which have a strength of from ten thousand to eighteen thousand pounds. Now, it is obvious that the traction-springs of these brakes should yield at least half their stroke to the resistance of a single car, or the car-brakes will not be taken off. A single car weighing eighty thousand pounds (more than ordinary weight) on a good level track should not offer resistance much greater than two hundred pounds. It will be seen, then, that in a train—say forty such cars—the traction-springs next to the engine would have about eight thousand pounds tractile resistance to oppose the ten thousand pounds strength of the ordinary spring, or nearly enough to take off the brake at the forward car; but going back, this force would be diminished car by car, so that on most of the cars of the train the brakes would remain set to a greater or less degree, increasing toward the rear of the train. It must be evident, therefore, that light springs must be used, and it is one of the essential features of my invention to employ weak traction-springs which may be overcome by the tractile resistance of a single car.

Across the inner end of the link G lies a light bar, H, which also rests in the bottom of a vertical slot in each side wall of the buffer, and is extended upward at each end, the two ends meeting in a sort of arch some distance above the cross-pin E, and being enlarged to form a basket-like support, H', for the weight I' at the inner end of the uncoupling-lever I. The ends of the cross-pin E pass through the upright parts of the bar H, and are rigidly set in them, so that whenever the pin C² is lifted the bar H is lifted with it, and is thus taken out of the way of an entering link. A chain, I², connects the upper end of the pin C² with the uncoupling-lever. The fulcrum I³ of this lever rests on a bracket projecting from the forward cross-beam of the car-platform, and is placed near the end to which the power is applied, in order to effect rapid operation, the weight to be lifted being slight. The bracket is horizontally pivoted to the beam, so that the position of the lever accommodates itself to the inward and outward movements of the buffer. The pin C² may be made so long that its lower end will touch the bottom of the buffer before it has reached the limit of downward motion allowed by the clevis, so that when the lower end of the pin is worn it can be cut off, and the pin will again be as serviceable as a new one.

The flanges of the coupler are considerably thickened at their forward ends, especially in the middle, where they come in front of the pin C², as shown in Figs. 6 and 8. This serves the double purpose of protecting the pin and of keeping the link straight; and the thick-

ening at the sides, which (though less than in the middle) is still considerable, affords a fulcrum for the link to oscillate on, so that it may accommodate itself to any difference of level in the two cars coupled. To facilitate the entry of the link into the buffer, the flaring mouth B' is concave above and below on its inner surface. At its inner end the buffer terminates in a sleeve, B³, in which the draw-bar has a longitudinal play, regulated by a coiled spring, D², which surrounds it between the nut D' and the rear end of the buffer. The rear end of the sleeve B³ passes through the front wall of the box-like frame K' of the main traction-spring K, and rests against the elastic washer or cushion K², which is itself close to the forward end of the spring. By this means the buffer itself is allowed a slight longitudinal play. The cushion has a central perforation large enough to allow the draw-bar to pass through, as it does also through a similar washer or cushion, K³, similarly placed at the rear end of the spring. The washer K³, however, terminates in a sleeve of diminished diameter, and a lug-nut, D³, is screwed on the rear end of the draw-bar and against the rear end of the sleeve, so that the draw-bar has no motion relatively to the washer K³. The spring K surrounds the draw-bar, and its two ends press, respectively, against the two washers. The sleeve portion of the washer K³ passes through the rear wall of the frame K'. The frame K' is fastened at both sides to the floor-timbers A, and the backward and forward movements of the buffer are limited by the contact of the rear and front washers, respectively, with the rear and front walls of the frame.

By means of the eyes of the lug-nut D², the bar or rod L, which connects the coupling with the brake mechanism, is hinged to the rear end of the draw-bar; or, if the coupling mechanism be used without connecting with the brake, a gravitation-lever may be suspended from these eyes, and will serve the purpose of a nut-lock.

The brake-bars M, which are arranged between the axles, are parallel to each other and perpendicular to the plane of the wheels at the ends, where the brake-shoes are attached, but are bent away from each other in their middle parts, so as to afford room between them for the toggle N, which operates them, and at the same time to keep the brake-shoes M' parallel to the convex surfaces of the wheels. Each arm of the toggle is bifurcated, as shown (partly by dotted lines) in Fig. 2, so that the motion of the toggle is kept vertical without the necessity of guides to prevent it from veering to the one side or the other. This construction also serves to distribute the stress on the brake-bar by applying the force at two points. The toggle is arranged, as shown in Fig. 3, so that the upward motion of the joint draws the brake-bars together, and so takes off the brakes, its downward motion having the reverse effect. The joint is rigidly con-

nected, as shown in Fig. 3, by a vertical rod, N', and cross-bar O', with the double bentlever O, which is pivoted at one end to the floor-beams A, passes downward below the toggle, and is operated at its forward end by the connecting-rod O², which is pivoted to it there, and which is also pivoted at its upper end to the double lever P. The rod O² is made in two lengths, which are held together by the binding-nut o², so that the rod is adjustable in length. The lever P is fulcrumed on the cross-bar P', which is rigidly attached to the under sides of the longitudinal beams A. The upper ends of the lever are joined by a cross-bar, p, which passes through the rod L, and is thus connected with the draw-bar and coupler. The rod L extends beyond the cross-bar p, and is connected at its inner end by a hook or link with one end of the vibrating arm Q. This arm is horizontally pivoted at its middle point to the rod R. This rod extends horizontally backward between the beams A and hooks into the coiled spring R', which is fastened at its other end to the bar R², set in the beams A at the inner end of the truck. The other end of the rocking arm Q is pivotally connected with the rod S, which extends forward between the beams A, and is connected with the chain S' of the ordinary hand-lever. The elasticity of the spring K naturally tends to force apart the washers K² and K³, between which it is confined, and thus to throw the draw-bar inward to the limit of the play which it has independently of the buffer. The spring R', which is connected with the rod L by means of the vibrating arm Q and the rod R, is so adjusted as partly to counteract this tendency of the spring K and hold the lever P and rod O² vertical, or nearly so, and thus draw down the free end of the bent lever O, thereby straightening the arms of the toggle and holding the brakes on. The brakes are thus always on unless some special force is exerted to take them off. This is supplied, when necessary, by the pull of the link on the pin C², and consequently on the buffer and the draw-bar, which is exerted as soon as the train begins to move forward. This pull draws the lever P and rod O² out of the vertical position, and thus lifts the free end of the lever O, thereby raising the joint of the toggle and drawing the brake-bars together, so that the brakes are taken off. This position of the mechanism is shown in Fig. 3 of the drawings. As soon as this pull ceases, which will be the case when the locomotive stops, the springs K and R' are left to their normal operation, which again applies the brakes. If, now, the locomotive should be backed, the buffer would be pushed inward, carrying the draw-bar with it, and again resulting in the deflection of the lever P and rod O² from a perpendicular, and consequently in the lifting of the joint of the toggle N and the taking off of the brakes, so that they would offer no

obstruction to the backing of the train. Thus I secure an automatic application of the brakes at all times (including the case of a car standing detached) when motion is not desirable, and an automatic removal of them whenever the train is drawn forward or pushed back. 70

I retain the ordinary hand-lever apparatus for the purpose of taking off the brakes when it is necessary to move a detached car. It 75 may also be used as an auxiliary to putting on the brakes of a train of cars at the start.

The lever O might be pivoted near the outer end of the truck, instead of the arrangement shown in the drawings. It would 80 then require a greater force to operate it, but would operate more rapidly.

At each end of the brake-bar I fasten the lower end of a strut-spring, T, whose upper end is fastened in like manner to the cross-beam. The tendency of these springs is to force the bars apart, and thus furnish an additional security that the brakes shall always be applied, except when for some special reason it is requisite to take them off. 85 90

What I claim as my invention, and desire to secure by Letters Patent, is—

1. The hollow open-mouthed buffer B, in combination with the coupler C, the pin C', rigidly affixed to the coupler, but arranged to 95 have a limited backward and forward play in the buffer, and the pin C', arranged to have a vertical play in both coupler and buffer and a limited longitudinal play in the former only, and means for lowering and raising the pin C', 100 substantially as and for the purpose described.

2. The buffer B, coupler C, upright pin C', horizontal pins E and E², guiding-rods E', and mechanism for lifting the pin E, all in combination, substantially as and for the purpose 105 described.

3. The buffer B, coupler C, upright pin C', horizontal pins E and E², guiding-rods E', bar H, shaped and arranged as described, spring F, arranged as described, and means for lifting the pin E, all in combination, substantially 110 as and for the purpose described.

4. In a traction car-brake, the bifurcated toggle-arms N and N', connected with and arranged to operate two or more brake-bars, in combination with readily-yielding draw-bars, and mechanism for connecting the knuckle of the toggle-arms with the draw-bar, substantially 115 as and for the purposes set forth.

5. The springs K and R', lever P, arranged 120 as described, mechanism connecting the springs with each other and with one end of the lever, rod O², arranged substantially as described, bent lever O, connecting-rod N', toggle N, and brake-bars M, all in combination, substantially 125 as and for the purposes described.

EDWARD B. MEATYARD.
